UNITED STATES PATENT OFFICE.

HENRY W. O'DOWD, OF JERSEY CITY, NEW JERSEY, ASSIGNOR TO WILLIAM M. CRANE COMPANY, A CORPORATION OF NEW YORK.

GAS STOVE.

1,425,043.

Specification of Letters Patent. Patented Aug. 8, 1922.

Application filed November 20, 1918. Serial No. 263,249.

To all whom it may concern:

Be it known that I, HENRY W. O'Dowd, a citizen of the United States, residing at Jersey City, in the county of Hudson and State of New Jersey, have invented certain new and useful Improvements in Gas Stoves, of which the following is a specification, reference being had therein to the accompanying drawings.

5 The invention relates to ranges or stoves that are operated with gaseous fuel, and it is particularly adapted for apparatus of this type for use in hotels, restaurants, and institutions wherein vast quantities of food 10 are cooked daily.

Ordinarily, the type of range above referred to has a top surface which is smooth and entirely covered with a plate or plates of metal, so that large vessels, kettles and 15 pots may be slid thereover from place to place as the service requires. It is desirable to have the surface very hot in the forward portion or at either end and gradually diminishing in temperature toward the 20 flue. For this purpose, the gas burners are located at the front of the range or at either end thereof and the flame from any or all of them is directed inwardly to an opposite portion of the top surface. In ranges of 25 the type, however, which fulfill these conditions, the flame usually is caused to impinge upwardly against the top of the stove, and when it strikes the cold metal, the burning mixture of gas and air condenses 30 and breaks up, giving off carbon monoxide. There is also a tendency to retard a supply of secondary air or air to support combustion at the point of contact, which further augments the noxious monoxide 35 exhalations.

40 A feature of the present invention is that it provides a new form of heat-generating chamber specially constructed and fitted for burning the gaseous fuel in such a manner as to nullify the chances of incomplete combustion, and consequently to obviate the danger of giving out carbon monoxide.

45 Another feature of the invention is that it makes provision for heating the top surface of the stove directly by heat radiation, and more or less indirectly by lateral contact of the flame.

50 Still another feature consists in providing a flame or battery of flames directed from one or more burners downwardly

against refractory, heat-radiating material, which is formed with an upward incline in its inner portion. While the material temporarily absorbs much of the heat emitted by the flame in its downward course, the 60 incline thereof diverts the flame up under the top, whence it proceeds between another section of like material and the lower face of the top, to the flue outlet.

An additional feature resides in having 65 the front section of the refractory material scored in parallel lines throughout the length thereof, and cross-scored in the width, thereby forming grooves and nodes that afford a multitude of channels for currents of air admitted through an aperture in the casing of the range. This front section constitutes the bottom of the heat-generating chamber in the preferred embodiment of the invention. The flame, being 70 downwardly directed, is covered by the air that overlies the burner, and meanwhile the longitudinal or from-front-to-back scoring of the refractory material enables a similar supply of secondary air to underlie the flame, the air thus flowing both above and beneath the same. The transverse scoring coacts with the longitudinal scores in diffusing the air around the nodes in the 75 refractory material, which are brought to 80 incandescence by the flame much more rapidly than would be the case with a smooth-surfaced material, and consequently give off 85 radiant heat in the minimum of time. Besides, the scoring and nodes act as a scrubber 90 on the flame by allowing it a more intimate contact with the secondary air, and thereby relieving it of its proclivity to generate carbon monoxide.

95 A supplementary feature is found in that the said front section of refractory material is cut away on its under side and at the rear so as to afford a passage for a further supply of secondary air to the flame as it travels towards the flue. This additional supply of air furnishes sufficient oxygen to liberate whatever heat units may still be stored up in the flame after it has left the heat-generating chamber.

100 Generally, the invention may be said to have for its object to produce an improved range or stove of the nature mentioned, which shall insure a perfect combustion of the gaseous fuel and cause it to yield an intensely hot flame, so applied to a cooking 110

surface or medium that the same will have the benefit of practically all the heat units which the fuel consumed will generate.

The invention consists in the novel parts, 5 combination, features of construction and improvements herein shown and described.

In the accompanying drawings which are referred to herein and form part hereof is 10 illustrated a preferred embodiment of the invention, the same serving in connection with the description herein to illustrate the principles of the invention.

Of the drawings:

Fig. 1 is a sectional side elevation of a 15 hotel range wherein the several features of construction above noted have been embodied;

Fig. 2 is a perspective view of a novel 20 form of oven bottom used in the said range;

Fig. 3 is a full front elevation of the same type of range;

Fig. 4 is a fragmentary sectional elevation, looking from the front;

Fig. 5 is a top plan view, partly broken 25 and partly sectioned to show the heat-generating chamber below the stove top and a portion of the oven underneath the same;

Fig. 6 is a partial plan related to the preceding view and showing the left-hand side 30 of the range with the adjoining portion of the heat-generating chamber and burners therein in horizontal section;

Fig. 7 is a partly-broken top plan view 35 of a range of similar type, but involving a modified arrangement of the component parts of the invention;

Fig. 8 is an end view of this modified form of the range; and

Fig. 9 is a partly-broken front elevation 40 illustrating an additional modification.

The body of the range may be of any approved design and construction. Thus it may consist, as shown, of a quadrangular casing 11, composed of a number of metal 45 castings and sheet-metal sections, suitably assembled and rigidly secured to one another. Preferably, the top is made entirely flat, and comprises border plates 12, with depending flanges 13, and marginal rabbits 14, supporting inset plates, as 15. The latter are heating plates functioned to carry the usual cooking utensils, and may be fashioned with usual orifices 16, covered by removable lids 17.

55 Directly under the plates 15 is a heat-generating chamber 20, shown in Fig. 1 as extending the full depth of the range and somewhat spaced from the sides of the casing 11 as indicated in Fig. 4. This chamber

60 is partly filled in front or at one side by blocks 21, of refractory, heat-radiating material, such as fire-brick or the like, and in the rear or laterally thereof contains slabs 22, of same material, laid upon metallic supports 23. The inner portions of the blocks

21 and the upper faces of the slabs 22 are practically at the same height, reaching up to within a very short distance from the heating-plates 15, but the outer portions of the blocks are considerably depressed to form 70 concavities 24, the curve whereof dips slightly below the upper external edge of the blocks and thence rises on an extended incline inward to the level of the neighboring slabs. The blocks are also cut away on 75 the outside, at the bottom and on the inside, as at 25, 26 and 27, to produce a wide air-channel between them and the adjoining inner face of the casing 11, the bottom of the chamber 20, and the superposed slabs 80 22 and supports 23, respectively. Moreover, the blocks are grooved longitudinally throughout and transversely across their middle portions to provide intersecting air-ducts 28 and 29, respectively, together with 85 intermediate nodes 30, formed thereby. The purpose of these several air passages has been partially pointed out in the beginning of this specification and will be further explained hereinafter. 90

Heat is generated in the chamber 20, preferably by burning fuel-gas therein, that is, either natural or artificial gas, which is brought up from a main supply-pipe or manifold 33, to air-mixing tubes 34, 35, 95 36, 37, through intermediate pipes 36, 37, and thence is fed to burners 38, 39, that may extend forwardly or laterally of the range under the outer ends of the heating plates 15, and are provided each with a plurality 100 of flame ports 40, 41. While the flame might be delivered into the heat-generating chamber by individual Bunsen burners, each having its own air regulator and a single fuel orifice, it is deemed preferable to use 105 two burners, as shown, with plural flame ports controlled from one air regulator and fuel supply. Due to this construction, there is obtained from each burner a battery of flames under each heating plate, and the 110 number of flames in either or any series may be varied to meet different requirements. In the present exemplification of the invention, the burner 38 is provided with three flame ports, while the burner 39 has 115 double that number, so that by lighting either burner, one at a time, or both burners together, in using the range it is possible to heat as much of the stove's surface as may be found advisable, such as one-third or two-thirds thereof, or the entire surface, according to the actual needs of the service. 120

The flame ports aforesaid are in the nature of relatively wide jets projecting inward from the burners and are preferably turned downwardly towards the depression 24, in the blocks 21. These jets are situated about midway between the under side of the heating-plates 15 and the concave 125 130

portion of the blocks. As depicted in Fig. 1, the flame is aimed at approximately the center of the concavity in the refractory material, and deflecting therefrom follows 5 up in its entirety the extended incline at the inner end of the depression; thence it passes over the slabs of refractory material behind; and finally the products of combustion are received in a chamber 44, located 10 under the flanged border plate 12, at the opposite side of the range from the burners. The latter-named chamber has a flue outlet 15, affording egress to the products of combustion.

15 The admission of gas to the burners 38 and 39 is controlled by rotary valves 48 and 49, respectively, placed one at each side of the range in front or at either end. The gas being turned on, either or both of the 20 burners can be lighted from a single pilot-light 50, which is positioned between the adjoining ends of the two burners above the outer edge of the refractory material 25 21, and connects by means of piping 51, with the branch-pipe 36, previously referred 30 to as conveying the gas from the manifold 33 to the air-mixing tube 34. A rotary valve 52 controls the flow of gas to the pilot-light. The latter, as will be understood, is 35 a continuous burner arranged to coact with the main burners, whether singly or jointly, so that they can be readily ignited.

An air-intake 55, extending the full width or depth of the heat-generating chamber 35 above described, is provided in the casing of the range, in proximity to the depressed portion of the heat-radiating material therein. The intake may be produced by cutting down the upper edge of the casing 40 45 11, or making it stop short of the border plate 12, either in front or at the side, as represented in Figs. 1, 3, 6 and 8. The resulting gap serves to admit into the heat-generating chamber an abundance of atmospheric air besides that mixed with the gaseous fuel in the tubes 34, 35, and also affords ample space for the introduction of the series of jets 40, 41, of the burners 38, 39. The secondary air thus admitted into 50 the heat-generating chamber promotes combustion of the gaseous fuel, and further creates a powerful draught that carries the flame from the jets to the remotest portion of the range under the heating-plates 15. 55 As indicated by the small arrows in the upper section of Fig. 1, the flame and the peculiar disposition of parts in the heat-generating chamber operate to divide this secondary air into several distinct strata, each performing its special function. One stratum may be said to overlie the flame, between the latter and the under face of the heating-plates 15. Another stratum underlying the flame, covers the grooved radiat- 60 65 ing blocks beneath the same. The flame is

enwrapped, so to say, in these two air strata, which not only insure the perfect combustion of the gaseous fuel, but at the same time prevent the incombustible products thereof from either settling down upon the 70 heat-radiating material or adhering to the heating-plates above. A third stratum of the secondary air follows the course of the channel defined by the cut-away portions 25, 26 and 27 of the blocks 21, and at the junction thereof with the slabs 22 unites with the second stratum in carrying the flame and products of combustion outwardly into the chamber 44.

It will be noted here, first, that as the gas-jets are of an inverted type and spaced away an appreciable distance from the heating-plates, the gas issuing therefrom under normal pressure cannot rise at once to the stove top, but instead directs the flame into 80 the concavity provided in the blocks of refractory material and gives it an impulse inward between the upper strata of the secondary air that enters the range through the intake and flows in towards the flue. The 85 products of combustion are thereby kept from contact with the heating-plates, at least until the upper end of the incline on the blocks is reached, and then the burning 90 gas has become thoroughly ablaze. Secondly, the refractory material, being subjected continually to the heat of the flame, is soon heated to incandescence and in turn 95 radiates heat upwardly to the superjacent plates of the stove top. The intensity of 100 the heat developed within the concavity of the radiating material is such that it accelerates the combustion of the gaseous fuel and quickly dissipates any ignitable substance therein contained. Thirdly, the longitudinal and transverse grooves in the surface of the heat-radiating blocks provide 105 the requisite passages for the complete diffusion of the secondary air under the flame without impeding the latter's action upon 110 the blocks, the nodes of which protrude upwardly into or through the flame. Fourthly, the inner portions of the top plates are heated both by conduction and by the heat of 115 the flame entrained by the double draught which the plural air-passages induce from the intake to the flue outlet. Fifthly, the slabs of refractory material under the said inner portions of the plates also absorb heat 120 from the inwardly trending flames and radiate it towards the top. Sixthly, the currents of air flowing through the various passages severally contribute or coact in conveying the flame and products of combustion to the chamber 44, and in extracting therefrom all of the heat units, the greater part of which is collected in the outer portion of the generating chamber, and the remainder in the inner portion of the same. Seventhly, 125 the products of combustion are carried out- 130

wardly and discharged into the chamber 44, wherein they spread and from which they escape through the flue outlet in a comparatively cold condition. It follows, therefore, 5 that the combustion of the gaseous fuel is actively maintained from the point of ignition thereof to the discharge of its inert products, and the temperature obtained is gradually retrocedent, most of the heat being 10 generated within or about the depression in the radiating material, and diminishing in intensity until the flame disappears in the vicinity of the last-named chamber. This is unlike the prevailing conditions in 15 other forms of heating apparatus, in which there occurs a considerable wastage of unused heat units that are lost with the products of combustion, and where as a consequence the flue is usually hotter than the 20 portion of the stove surface adjoining it. The present construction conserves the heat, and, besides, the gaseous fuel consumed therein leaves no soot deposit on the under-side of the heating-plates nor upon the radiating 25 material below.

This type of range can also be equipped with an oven for roasting, baking and analogous culinary operations. In the embodiment of the invention illustrated in the 30 drawings, the oven consists of a single enclosure 58, which however may be divided into a plurality of sections, if desired. As shown, the oven 58 is heated from the same fuel supply as that employed for generating 35 the heat in the upper chamber before described. The gaseous fuel is obtained from the central portion of the manifold 33, through valved couplings 59, which deliver it into air-mixers 60, set in the front wall 40 of the range, near the bottom. From the mixers 60, the gas flows into burner tubes 61, provided with a plurality of ports 62, through which it is distributed in a lower heat-generating chamber 63. The gas is ignited 45 at the ports 62, by means of Y-shaped pilot-burners, only one branch of which is shown in Fig. 1 and is there designated by the reference numeral 64. Secondary air to promote combustion is admitted into the 50 chamber 63, through apertures 65 in the bottom thereof, and may be drawn from an under compartment supplied from the exterior of the range, at the rear, by a plurality of inlets 66. See Figs. 1, 3, 4 and 9. 55 It is of paramount importance to retain all of the available heat as long as possible inside of the oven, and therefore means are employed to check its too rapid ascension, as well as to diffuse and distribute it equally 60 throughout the oven. To accomplish this, the oven 58 is built with a baffle or raised bottom 67, located directly above the burners 61, and is provided with side openings 68, see Fig. 4, which admit the heat into the 65 body of the oven at different levels above

the bottom. From the interior of the oven, the ascending heat currents and products of combustion are led through similar openings 69, made in a top plate 70, which constitutes the bottom of a horizontal flue 71, underlying the upper heat-generating chamber 20, and discharging into a sub-compartment 72, of the back chamber 44. The interior of the oven, it is understood, may contain a number of shelves (not shown) adapted for sliding in and out upon side rests 73, see Figs. 4 and 9. Opposite the openings 68, on either side of the oven, are metal linings or internal walls 74, spaced some distance inwardly from the jacket or casing 11 80 of the range. At predetermined points on these walls or linings, and above the openings 68 in the oven's sides, heat staggerers or blockades 75 are placed, which regulate the quantity of heat that can be delivered 85 into that portion of the interior of the oven.

The oven bottom or baffle 67, above referred to, may consist of a plurality of metal plates placed end to end, as in Fig. 1, and supported at the edges upon a pair of 90 the side rests 73, also previously mentioned. One of these plates is shown in perspective in Fig. 2. Preferably, each plate 67 is formed with strengthening ribs 78 on the under side, and is further provided with 95 ridges 79 on its upper surface, which are staggered to promote circulation of the diffused heat from the bottom. These ribs and ridges also serve to absorb heat which is utilized in the various cooking processes. 100 By resting the cooking utensil upon the ridges 79 rather than directly upon the flat surface of the bottom 67, moreover, any liability of burning or overheating the material being cooked, due to too rapid absorption of the heat, is avoided. As represented in Fig. 1, the oven is furnished with a drop-door 80, and the plates 67 are situated slightly below the lower edge thereof, so that when the door is fully open, its inner 110 face lies on a level with the ridges projecting from the plates. A roasting or baking pan can easily be slid into and out of the oven, by having the door and ribbed plates relatively so disposed.

The door 80 aforesaid is already covered by Patent No. 1,228,042, dated May 29, 1917, and therefore its construction need not be particularized herein. However, a further improvement is embodied in the means for 120 resisting the shock to the range when the door falls or is dropped into open position. In accordance with the construction set forth in the said patent, shock blocks were placed against the body or front of the 125 range, to receive the impact of the falling door. The present method of carrying out this part of the invention is to take the shock on the manifold supports. As illustrated in Figs. 1, 3, 8 and 9, the manifold 33 130

rests in bearings 81, secured to supports 82, at the base of the range, in front. The door is hinged at its lower edge above these supports, and on its opposite sides is held by means of telescoping members 83, having ball-and-socket connections, as 84, with both supports, forwardly of the hinge pintles. The supports are cast with recesses 85 for the purpose of effecting appropriate joints, and the supports are made to rest on the floor below the manifold, besides being fastened to the latter and to the body of the range. Thus, the resistance to the shock of the drop-door is obtained principally from the floor, instead of exclusively from the range body as in the former construction.

Figs. 7, 8 and 9 differ from the other views of the drawings to the extent that they illustrate a form of range wherein the flame originates at one side or end, and is directed towards the opposite side or end, instead of being delivered at the front and thence carried rearwardly. Thus, taking the front of the stove to be as usual the part thereof where the oven door 80 is located, the inset plates, indicated by the reference character 15^a, extend from the left to the right, as clearly seen in Fig. 7, and the heat-generating chamber 20^a, see Fig. 9, runs in the same direction. Consequently, the burners 38^a and 39^a are positioned at the left end in this modified construction of the range, and the flue-outlet 45^a is situated at the right end. The outlet 45^a, it will be observed particularly with reference to Fig. 7, need not be directly opposite either group of burners, nor centered with relation to the air-intake 55^a, but it may be at or near one corner of the range; as the latter-named figure shows.

The manifold 33, however, is preferably kept at the base of the stove in front. From the manifold, the fuel-gas is conveyed to the air-mixers 34^a, 35^a, through pipes 36^a, 37^a, and from the mixers to the burners 38^a, 39^a, the latter having the flame ports 40^a, 41^a, and being ignited from an intermediate pilot-light 50^a. All of these parts are placed at the left end of the stove, in the illustration given, but they could be located as well at the right end, if preferred, with obvious alterations.

A further modification, embodied alone in Fig. 9, consists in coupling together end to end a plurality of stove units constructed in accordance with the present invention. It will be noted that, pursuant to this other modified construction, a single manifold is utilized to supply the said units with the gaseous fuel, and the service pipes and burners may be lodged between adjacent units, leaving the entire front of the range unincumbered by any such appliances.

The invention, in its broader aspect, is not restricted to the precise details of construction and arrangement of parts herein

disclosed, nor to any specific manner of carrying it into practice, as manifestly numerous changes and modifications can be effected without departing from the underlying principles of the invention, or sacrificing any of its chief advantages.

I claim:

1. A stove including a heating plate, a subjacent burner with a flame port directed downwardly away therefrom, and means underlying the burner and arranged in close proximity to the heating plate for radiating towards said plate the heat produced by said burner. 75

2. A stove including a heating plate, an air-insulated source of heat extending thereunder, and a radiating element arranged to reflect directly towards said plate the heat directly received from said source. 80

3. A stove including a heating plate, a radiating element beneath the same, an intermediate source of heat directly impinging upon said element, and means serving to interpose between said plate and said source a stratum of air extending past the point 90 impinged by the heat. 85

4. A stove including a heating plate, a subjacent burner turned in a downward direction away therefrom, a radiating element heated by impingement of the flame from 95 said burner, and means conveying a current of air to the flame as it strikes said element.

5. A stove including a heating plate, a radiating element positioned in proximity thereto, a burner directing angularly against 100 said element a flame to be reflected thereby toward said plate, and means serving to pass currents of air above and below said flame.

6. A stove including a heating plate, a radiating element located below the same, a burner directing a flame downwardly against 105 said element, means conveying a current of air between the latter and said plate under the forward part thereof, and means leading 110 air to the flame past said element under the rear part of the plate.

7. A stove including a heating plate, a subjacent heat-radiating element, an intermediate air-passage having an intake forwardly of said element and an outlet rearwardly thereof, and a burner projecting a flame downwardly inward between air strata from said intake. 115

8. A stove including a heating plate, a passage thereunder having an air-intake at one end and an outlet at the opposite end, a heat-radiating element in line with said air-intake, a burner directing a flame downwardly against the surface of said element, 120 and an auxiliary air-channel below the latter connecting with said passage forwardly of 125 said outlet.

9. A stove including a heating plate, a heat-radiating element beneath the same, 130

- 6 a burner directing a flame downwardly against said element, a passage through which the flame passes, and means producing a double draught of air through said passage.
10. A stove including a heating plate, an air passage extending thereunder, a heat-radiating element located in said passage at the forward end thereof, a burner directing a flame downwardly against said element, and an auxiliary channel conveying air beyond the latter to said passage at the rear end.
15. A stove including a heat-generating chamber closed at the sides, top and bottom, an air-passage extending from the front to the rear thereof, a heat-radiating element in said chamber, and a burner directing a flame downwardly upon said element.
20. 12. A stove including a heat-generating chamber adapted to be covered at the top and closed at both sides and bottom, an air passage extending therethrough from front to rear, a heat-radiating element in the lower forward part of said passage, a burner directing a flame within the latter downwardly against said element, and a flue drawing the products of combustion from the rear part of the passage.
25. 13. A stove including an upper heat-generating chamber, an air passage extending horizontally therethrough, a heat-radiating element projecting upwardly into said passage within the forward part thereof, a burner directing a flame downwardly against said element, a flue subjacent to the latter having a communication with the rear of the passage, and a lower source of heat discharging into said flue.
30. 14. A stove including a heating plate, a concave heat-radiating element located thereunder, a burner directing a flame downwardly into the concavity of said element to be reflected thereby toward said plate, and means supplying to the flame currents of air moving along the opposed faces of the plate and element respectively.
35. 15. A stove including a chamber closed at the top, sides and bottom, an air passage extending horizontally therethrough, a heat-radiating element in said passage having a concavity with an upward incline at the rear thereof, and a burner directing a flame downwardly against said element within said concavity.
40. 16. A stove including a heating plate, an inverted burner positioned beneath the same, and a heat-radiating element with a nodose surface turned toward said plate and impinged upon by the downwardly directed flame of said burner.
45. 17. A stove including a heating plate, an air passage extending thereunder, an inverted burner in said passage, and a grooved radiating element projecting into the passage in position to receive the downwardly-directed heat from said burner and reflect it toward said plate.
50. 18. A stove including a heating plate, a heat-generating chamber subjacent thereto, a relatively depressed radiating element in the forward part of said chamber, a burner directing a flame downwardly upon said element, and a supplementary heat-radiating member located nearer to said heating plate at a distance from said burner.
55. 19. A stove including a heating plate, an air passage extending thereunder, a relatively depressed heat-radiating element projecting into the forward end of said passage, a burner directing a flame downwardly upon said element, an auxiliary channel conveying air beyond the latter to the rear end of the passage, and a supplementary heat-radiating member located in proximity to said heating plate behind said channel.
60. 20. A stove including a heating-plate, a sublying heat-generating chamber, a plurality of gas-jets projecting downwardly into the latter, radiating elements placed at the bottom of said chamber in position to be impinged upon directly by flames from said jets, and means supplying combustion-supporting air over and under said flames.
65. In testimony whereof, I have affixed my signature hereto.

HENRY W. O'DOWD.
